UNITED STATES PATENT OFFICE.

JAMES M. CUMMING, OF NEWARK, NEW JERSEY.

BOTTLE-CLOSURE.

No. 880,723.

Specification of Letters Patent.

Patented March 3, 1908.

Application filed March 21, 1907. Serial No. 363,567.

To all whom it may concern:

Be it known that I, JAMES M. CUMMING, a citizen of the United States, residing at Newark, in the county of Essex and State of New Jersey, have invented certain new and useful Improvements in Bottle-Closures; and I do hereby declare the following to be a full, clear, and exact description of the invention, such as will enable others skilled in the art to 10 which it appertains to make and use the same, reference being had to the accompanying drawings, and to characters of reference marked thereon, which form a part of this specification.

15 The present invention has reference, generally, to improvements in bottle-closures; and the present invention relates, more particularly, to a novel form and construction of lock-cap or closing device which may be 20 placed over the mouth and the neck of a bottle and locked in its relation thereto, thereby protecting and securing the bottle-cork or stopper in the bottle and preventing its removal therefrom, until the lock-cap has 25 been unlocked and removed from its engagement with the neck of said bottle.

The invention has for its principal objects to provide a novel and simply constructed device which shall be neat and ornamental, 30 and is especially designed for the purposes hereinabove stated; and, furthermore, to provide a device which protects the bottle-cork or stopper from removal from the bottle-neck, to prevent the contamination of 35 the liquid contained in the bottle, and to prevent it from being stolen or accidentally used.

A further object of this invention is to provide a novel, cheap and simply constructed device which may be readily adapted 40 to different sized bottles to prevent the removal of the bottle-cork or stopper therefrom.

A further object of this invention is to provide a device for the purposes hereinabove stated, whereby liquids having considerable value which are contained in the bottle, are protected against loss by theft, accidental removal of the bottle-cork or stopper and 50 such similar contingencies. Furthermore, the contents of bottle containing poisons, medicines, and the like may be protected, and their accidental use or removal guarded against, by the use of the device embodying 55 the principles of the present invention.

Other objects of the present invention, not

at this time more particularly set forth, will be clearly indicated in the accompanying specification and then finally embodied in the clauses of the claims which are appended 60 to and which form an essential part of this specification.

With these several objects in view, the present invention consists in the various novel arrangements and combinations of the parts comprising the device, as well as in the details of the construction of the said parts, all of which will be hereinafter more fully set forth, and then finally embodied in the clauses of the claims.

70 The invention is clearly illustrated in the accompanying drawings, in which:

Figure 1 is a side elevation of a portion of a bottle illustrating the device embodying the principles of the present invention in its locked relation with the neck thereof; and Fig. 2 is a top or plan view of the same. Fig. 3 is a horizontal section taken on line 3—3 in said Fig. 1 looking in a downward direction; and Fig. 4 is a similar section illustrating the device in its unlocked or detachable relation with the neck of the bottle, both of said sections being made on an enlarged scale. Fig. 5 is a horizontal section taken on line 5—5 in said Fig. 1, also looking 85 in a downward direction. Fig. 6 is a vertical cross-section of the lock-cap and bottle-neck, taken on line 6—6 indicated in said Fig. 3. Fig. 7 is a detail vertical cross-section of the lock cap, illustrating more particularly the means for securing the parts thereof in their operative relation with each other. Fig. 8 is a detail vertical cross-section, taken on line 8—8 in said Fig. 2, looking in the direction of the arrow x, and 90 illustrating more particularly the locking means for locking the movable parts of the lock-cap. Fig. 9 is a horizontal cross-section of the same, said section being taken on line 9—9 in said Fig. 8, and illustrating a key 95 inserted in the lock of said lock-cap or closing device. Fig. 10 is a horizontal section, similar to that shown in Fig. 3, but illustrating a slightly modified form of bottle-neck and lock-cap; and Fig. 11 is a vertical cross-section of the same, said section being taken on a line 11—11 indicated in Fig. 10.

100 Similar characters of reference are employed in all of the said above described views to indicate corresponding parts.

110 Referring now to the accompanying drawings, the reference-character 1 indicates the

complete lock-cap or closing device embodying the principles of the present invention, the same being adapted to be locked in its relation with a bottle 2, the neck of said bottle being provided with a shoulder 3. The said bottle 2 is provided with the usual cork or stopper 4 adapted to be thrust in the mouth of the neck of the bottle in the usual manner. The said lock-cap 1 comprises, essentially, a cap-member 5 which is provided upon its lower periphery with an outwardly extending shoulder or flange 6, this said shoulder or flange being provided upon its under side with cutaway portions or small chambers, each cut-away portion being constructed to form a cam 8 at one end of said cut-away portion 7 and a cam 9 at the other end thereof. Adapted to be maintained in a slidable relation with the under side of said shoulder or flange 6 is a lock-pawl actuating ring 10, upon the upper surface of which are pivotally arranged on suitable posts or pivots 11, suitably constructed pawls or dogs 12, substantially as shown. These lock-pawls or dogs 12 are adapted to be movably arranged in the cut-away portions 7 of said shoulder or flange 6. The said lock-pawl engaging ring 10 is provided with suitably disposed lots 13, through which pass rivets or pins 14 which are adapted to secure in rigid engagement with said shoulder or flange 6 a ring 15 arranged beneath the ring 10, the slots 13 permitting the lock pawl engaging ring 10 to be turned or moved in its relation to said shoulder or flange 6 and the ring 15 secured thereto.

Secured by means of solder or in any other suitable manner upon the upper side of said shoulder or flange 6 and against the outside of the cap-member 5 is a lock-casing 16, which is provided with a key-hole 17, arranged opposite a post 18 secured within the said lock-casing 16. Secured within the said lock-casing 16 is a plate 19 provided with a hole or perforation 20 through which passes a lock-bolt 21 said lock-bolt being adapted to project down through an opening or hole 22 in said flange or shoulder 6. The plate 19 is further provided with cut-away portions 23 which correspond with the formation of a key 24 and allow the same to pass said plate 19 to engage with an outwardly extending arm 25 of the said lock bolt 21 to raise the same, when the key is turned. A spring 26 is secured by means of rivets or other suitable means to the upper and inner side of said lock-casing 16, the free end of said spring being adapted to engage with the outwardly extending arm 25 of said lock bolt 21 to normally force said lock bolt in a downward direction. The said lock pawl engaging ring 10 is provided with a ratchet or a series of teeth 27 which project upwardly into a cutaway portion 28 in said

shoulder or flange 6. The said lock bolt 21 is adapted to engage with one of the teeth or ratchets 27 and thereby lock the lock-pawl engaging ring 10 to prevent its being turned in its relation with the said shoulder or flange 6, as will be clearly understood.

Referring now more particularly to Figs. 10 and 11 of the drawings there is illustrated therein a slightly modified construction of bottle neck and lock-pawl or dog to be used therewith. The cap-member 5 is constructed with the shoulder or flange 6, the lock-pawl ring 10 and the ring 15 secured to the said shoulder or flange 6 by the rivets 14 as above described, but pivotally arranged upon each post 11 is a lock-pawl or dog 29 provided at its free end with a wedge-shaped member 30 which is adapted to engage with a groove 31 in the neck of the bottle 2, instead of the shoulder as described in the first construction, the other mechanism used in this construction of lock-cap being the same as above described.

In both of the above described constructions, the lock-pawl engaging ring 10 is beyond the periphery of the shoulder or flange 6 and the ring 15 and may be knurled with a knurl 32 to facilitate its manipulation.

Having thus described the device in detail, it remains to describe the operation thereof in locking and unlocking the same in its relation with the bottle-neck. To lock the lock-cap or closing device in its relation with the bottle-neck, the said lock-cap is inserted over the bottle-neck in which the bottle-cork or stopper is in place. A key 24 is then inserted in the lock-casing 16 and is turned in an upward direction until it engages with the outwardly extending arm 25 of the lock-bolt 21 whereby the lock bolt is lifted in an upward direction and disengaged from its holding engagement with the notches or ratchet 27 of the lock-pawl engaging ring 10, whereupon said lock-pawl ring may be turned in its relation to the shoulder or flange 6 until the lock-pawls 12 come in contact with the cams 8 which forces said lock-pawls in an outward direction so that the free ends thereof engage with the under side of the shoulder 3 of the bottle neck to prevent the lock cap from being withdrawn from the bottle neck. The key 24 is then withdrawn from the lock, and the lock-bolt 21 drops down and engages with one of the teeth or ratchets 27, whereupon the lock-pawl ring is locked rigidly with the shoulder or flange 6 and the lock-pawls or dogs 12 are thus maintained in the positions above described. To remove or unlock the lock-cap, the key 24 is again used to disengage the lock-bolt 21 from the teeth or ratchet 27 of the lock-pawl ring 10, whereupon said lock-pawl ring is turned in the opposite direction, until the lock-pawls or dogs 12 are brought in engagement with the cams 9 which force the

- free ends of the said lock-pawl or dogs 12 away from their holding positions beneath the shoulder 3 of the bottle-neck until they are turned within the cutaway portion 7. 5 The lock-cap or closing device may thereupon be withdrawn from its relation with the bottle-neck and the bottle-cork or stopper exposed for its removal from the mouth of the neck of the bottle.
- 10 It will thus be understood from the above description that the present invention discloses a simple, neat, and easily manipulated device, by means of which the contents of a bottle may be locked therein against contamination, or against being stolen, the contents of the bottle being capable of removal only by the person who possesses the key.
- I claim:—
1. A bottle-closure for the necks of bottles, comprising a closing-cap adapted to be arranged over the mouth and down the outer sides of the neck of a bottle, a series of retaining pawls, and means for forcing the said retaining pawls into holding engagement with portions of the outer surfaces of the neck of the bottle.
  2. A bottle-closure for the necks of bottles, comprising a closing-cap adapted to be arranged over the mouth and down the outer sides of the neck of a bottle, combined with retaining devices adapted to be brought in engagement with the neck of the bottle, and a key-released mechanism with which said retaining devices are connected for forcing the said retaining devices in holding engagement with portions of the outer surfaces of the neck of the bottle, substantially as and for the purposes set forth.
  3. A bottle-closure for the necks of bottles, comprising a closing-cap adapted to be arranged over the mouth and down the outer sides of the neck of a bottle, an actuating ring movably connected with said cap, and retaining devices connected with said ring, adapted to be brought into holding engagement with portions of the outer surfaces of the neck of the bottle when said ring is moved in one direction.
  4. A bottle-closure for the necks of bottles, comprising a closing-cap adapted to be arranged over the mouth and down the outer sides of the neck of a bottle, an actuating ring movably connected with said cap, and retaining devices connected with said ring, adapted to be brought into holding engagement with portions of the outer surfaces of the neck of the bottle when said ring is moved in one direction, and means for locking said ring against movement, substantially as and for the purposes set forth.
  5. A bottle-closure for the necks of bottles, comprising a closing-cap adapted to be arranged over the mouth and down the outer sides of the neck of a bottle, an actuating ring movably connected with said cap, and a ring movably connected with said cap, and means for locking said ring against movement, substantially as and for the purposes set forth.
- retaining devices connected with said ring adapted to be brought into holding engagement with portions of the outer surfaces of the neck of the bottle when said ring is moved in one direction, and means for locking said ring against movement, consisting, of a series of teeth on said ring, a lock-casing on said cap, and a key-actuated bolt in said lock-casing having its end-portion in holding engagement with said teeth, substantially as and for the purposes set forth. 70
6. A bottle-closure for the necks of bottles, comprising a closing cap adapted to be arranged over the mouth and down the outer sides of the neck of a bottle, an actuating ring movably connected with said cap, a series of retaining pawls pivotally connected with the said ring, said pawls being adapted to be brought in retaining or holding engagement with portions of the outer surfaces of the neck of the bottle, substantially as and for the purposes set forth. 75
7. A bottle-closure for the necks of bottles, comprising a closing-cap adapted to be arranged over the mouth and down the outer sides of the neck of a bottle, an actuating ring movably connected with said cap, a series of retaining pawls pivotally connected with the said ring, said pawls being adapted to be brought in retaining or holding engagement with portions of the outer surfaces of the neck of the bottle, and means for locking said ring against movement, substantially as and for the purposes set forth. 80
8. A bottle-closure for the necks of bottles, comprising a closing-cap adapted to be arranged over the mouth and down the outer sides of the neck of a bottle, an actuating ring movably connected with said cap, a series of retaining pawls pivotally connected with the said ring, said pawls being adapted to be brought in retaining or holding engagement with portions of the outer surfaces of the neck of the bottle, and means for locking said ring against movement, substantially as and for the purposes set forth. 85
9. A bottle-closure for the necks of bottles, comprising a closing-cap adapted to be arranged over the mouth and down the outer sides of the neck of a bottle, an annular flange connected with said closing cap, a ring, and means connected therewith for securing said ring to said annular flange, a second ring movably arranged upon said first mentioned ring, and retaining devices connected with said second ring, substantially as and for the purposes set forth. 90
10. A bottle-closure for the necks of bottles, comprising a closing-cap adapted to be arranged over the mouth and down the outer sides of the neck of a bottle, an annular 100
- 110
- 120
- 125
- 130

flange connected with said closing cap, a ring, and means connected therewith for securing said ring to said annular flange, a second ring movably arranged upon said 5 first mentioned ring, and retaining devices connected with said second ring, and means for locking said ring against movement, substantially as and for the purposes set forth.

11. A bottle-closure for the necks of bottles, comprising a closing-cap adapted to be arranged over the mouth and down the outer sides of the neck of the bottle, an annular flange connected with said closing cap, a ring, and means connected therewith for securing said ring to said annular flange, a second ring movably arranged upon said first mentioned ring, and retaining devices connected with said second ring, and means for locking said ring against movement, 15 consisting, of a series of teeth on said ring, a lock-casing on said cap, and a key-actuated bolt in said lock-casing having its end-portion in holding engagement with said teeth substantially as and for the purposes set forth.

12. A bottle-closure for the necks of bottles, comprising a closing-cap adapted to be arranged over the mouth and down the outer sides of the neck of the bottle, an annular flange connected with said closing cap, said flange being provided with a series of small chambers, a ring, and means connected therewith for securing said ring to said annular flange, a second ring movably arranged 30 upon said first-mentioned ring, and a series of retaining pawls pivotally connected with said second ring, each pawl being arranged in a chamber of said flange and having an end-portion extending from said chamber and being 35 adapted to be brought in holding or retaining engagement with portions of the outer surfaces of the neck of the bottle, substantially as and for the purposes set forth.

13. A bottle-closure for the necks of bottles, comprising a closing-cap adapted to be arranged over the mouth and down the outer sides of the neck of the bottle, an annular flange connected with said closing-cap, said flange being provided with a series of small 45 chambers, a ring, and means connected therewith for securing said ring to said annular flange, a second ring movably arranged upon said first-mentioned ring, and a series of retaining pawls pivotally connected with said 50 second ring, each pawl being arranged in a chamber of said flange and having an end-portion extending from said chamber and being adapted to be brought in holding or retaining 55 engagement with portions of the outer surfaces of the neck of the bottle, and means for locking said ring against movement, substantially as and for the purposes set forth.

14. A bottle-closure for the necks of bottles, comprising a closing-cap adapted to be 60 arranged over the mouth and down the outer

sides of the neck of the bottle, an annular flange connected with said closing-cap, said flange being provided with a series of small chambers, a ring, and means connected therewith for securing said ring to said annular flange, a second ring movably arranged upon said first-mentioned ring, and a series of retaining pawls pivotally connected with said second ring, each pawl being arranged in a chamber of said flange and having an end-portion 70 extending from said chamber and being adapted to be brought in holding or retaining engagement with portions of the outer surfaces of the neck of the bottle, and means for locking said ring against movement, consisting, of a series of teeth on said ring, a lock-casing on said cap, and a key-actuated bolt in said lock casing having its end-portion in holding engagement with said teeth, substantially as and for the purposes set forth.

15. A bottle-closure for the necks of bottles, comprising a closing cap adapted to be arranged over the mouth and down the outer sides of the neck of the bottle, an annular flange connected with said closing cap, a 75 ring, a series of pins extending upwardly from said ring for securing the same to said annular flange, a second ring movably arranged upon said first-mentioned ring, said ring being provided with slots in which said 80 portions of the pins are arranged to limit the oscillatory movements of said second ring, and retaining devices connected with said second ring, substantially as and for the purposes set forth.

16. A bottle-closure for the necks of bottles, comprising a closing cap adapted to be arranged over the mouth and down the outer sides of the neck of the bottle, an annular flange connected with said closing cap, a 90 ring, a series of pins extending upwardly from said ring for securing the same to said annular flange, a second ring movably arranged upon said first-mentioned ring, said ring being provided with slots in which said 95 portions of the pins are arranged to limit the oscillatory movements of said second ring, and retaining devices connected with said second ring, substantially as and for the purposes set forth.

17. A bottle-closure for the necks of bottles, comprising a closing cap adapted to be arranged over the mouth and down the outer sides of the neck of the bottle, an annular flange connected with said closing cap, a ring, a series of pins extending upwardly from said ring for securing the same to said annular flange, a second ring movably arranged upon said first mentioned ring, said ring being provided with slots in which said portions of the pins are arranged to limit the oscillatory movements of said second ring, and retaining devices connected with said second ring, and means for locking said ring against movement, substantially as and for the purposes set forth.

18. A bottle-closure for the necks of bottles, comprising a closing cap adapted to be arranged over the mouth and down the outer sides of the neck of the bottle, an annular flange connected with said closing cap, a ring, a series of pins extending upwardly from said ring for securing the same to said annular flange, a second ring movably arranged upon said first-mentioned ring, said ring being provided with slots in which said portions of the pins are arranged to limit the oscillatory movements of said second ring, and retaining devices connected with said second ring, and means for locking said ring against movement,

- consisting, of a series of teeth on said ring, a lock-casing on said cap, and a key-actuated bolt in said lock casing having its end portions in holding engagement with said teeth, substantially as and for the purposes set forth.
18. A bottle-closure for the necks of bottles, comprising a closing cap adapted to be arranged over the mouth and down the outer sides of the neck of the bottle, an annular flange connected with said closing-cap, said flange being provided with a series of small chambers, a ring, a series of pins extending upwardly from said ring for securing the same to said annular flange, a second ring movably arranged upon said first-mentioned ring and a series of retaining pawls pivotally connected with said ring, each pawl being arranged in a chamber of said flange and having an end-portion extending from said chamber and being adapted to be brought in holding or retaining engagement with portions of the outer surfaces of the neck of the bottle, substantially as and for the purposes set forth.
19. A bottle-closure for the necks of bottles, comprising a closing-cap adapted to be arranged over the mouth and down the outer sides of the neck of the bottle, an annular flange connected with said closing-cap, said flange being provided with a series of small chambers, a ring, a series of pins extending upwardly from said ring for securing the same to said annular flange, a second ring movably arranged upon said first-mentioned ring, and a series of retaining pawls pivotally connected with said ring, each pawl being arranged in a chamber of said flange and having an end-portion extending from said chamber and being adapted to be brought in holding or retaining engagement with portions of the outer surfaces of the neck of the bottle, and means for locking said ring against movement, consisting, of a series of teeth on said ring, a lock-casing on said cap, and a key-actuated bolt in said lock casing having its end-portion in holding engagement with said teeth, substantially as and for the purposes set forth.
20. A bottle-closure for the necks of bottles, comprising a closing cap adapted to be arranged over the mouth and down the outer sides of the neck of the bottle, an annular flange connected with said closing-cap, said flange being provided with a series of small chambers, a ring, a series of pins extending upwardly from said ring for securing the same to said annular flange, a second ring movably arranged upon said first-mentioned ring, and a series of retaining pawls pivotally connected with said ring, each pawl being arranged in a chamber of said flange and having an end-portion extending from said chamber and being adapted to be brought in holding or retaining engagement with portions of the outer surfaces of the neck of the bottle, and means for locking said ring against movement, substantially as and for the purposes set forth.

In testimony, that I claim the invention set forth above I have hereunto set my hand this twentieth day of March, 1907.

JAMES M. CUMMING.
